PROCESS OF GEMMING INSOLES

Elmer A. Ellis, Medford, Mass.

Application October 31, 1930. Serial No. 492,428

1 Claim. (Cl. 12—146)

My present invention is an improvement in the art of preparing insoles for use in the manufacture of boots and shoes and is directed more particularly to the so-called gemmed insole.

5 Heretofore it has been customary to utilize a reinforcing layer of canvas or the like textile material on welt insoles to give a better sewing rib structure, thereby reinforcing both the insole and the rib with the canvas and permitting 10 thin and cheap leather to be utilized for the insole. Such prior gemming processes have utilized a specially prepared and treated canvas which had to have a priming or friction coating of rubber or the like, generally rubber and cement, 15 in order to adhere to the adhesive utilized to hold the canvas layer and leather insole together.

In my present invention I eliminate the necessity for specially treating the canvas for gemming insoles and also eliminate the coating of the canvas with adhesive and, furthermore, utilize a simple method of applying the reinforcing layer and, preferably, treat the insole alone with a coating of adhesive which will permit the canvas layer to be simply applied and pressed into shape 25 by the usual pressing devices. While I can utilize plain canvas without the priming or friction coating heretofore necessary, I may, and preferably do, apply to the edge portion of the canvas a thin layer of a suitable adhesive to prevent raveling of the textile layer at the edge. This permits 30 me to coat the canvas in very narrow strips of substantially correct width for the insole to which it is applied; eliminating waste of the material and simplifying the subsequent trimming operations.

35 Referring to the drawing illustrating the preferred embodiment of the present invention,

Fig. 1 is a plan view of my prepared insole with the adhesive coating applied ready to receive the 40 canvas;

Fig. 2 is a view of a sheet of reinforcing canvas in its natural state without a priming or other coating;

Fig. 3 illustrates the application of the reinforcing to the prepared insole;

Fig. 4 shows the completed gemmed insole, and

Fig. 5 is a cross-sectional view on the line 5—5 of Fig. 4.

Referring to the drawing, 1 indicates a welt 50 insole of any usual or desired style, size and contour, wherein the same has been channeled around the edge portion to form the sewing lip or rib comprised of the layers 3 and 5 cut from the channels 2 and 4 respectively. To the inner 55 surface of the channeled portion of the insole I

apply a coating of adhesive 6, said adhesive having a special affinity for the leather and canvas layer. This coating is applied on the flesh side of the leather constituting the insole 1 and is preferably of suitable consistency so as to remain in 60 "tacky" condition for several hours or days. Thus with the prepared insole so treated same can be coated in substantial quantities and shipped and used when ready.

To constitute the reinforcing layer I prefer to 65 coat the canvas 7 in any narrow strips of special width for the maximum required for the type of insole being gemmed and then coat the same of appropriate length from heel to toe and apply the canvas to the tacky surface of the previously coated insole. Preferably also, as I am using relatively narrow strips of canvas I may coat the edge portions as indicated at 9 and 10 which will keep same from unraveling and practically give the effect of a selvage edge along 70 the sewing rib at the forepart where a selvage is desirable without the expense incident thereto. Thus I am enabled to coat the canvas strips from large sheets of substantially exact dimension as to width, eliminating waste in the canvas, as well as of course eliminating the previous operations of sizing, friction coating, or 75 the like. The canvas 7 is then applied to the coated insole 1 and the gemming processes completed.

As shown in Figs. 4 and 5 the canvas layer 7 will preferably be gemmed with the coated edge portion substantially at the edges of the composite sewing rib, at which reinforcing, as illustrated at the right in Fig. 5, occurs the greatest 80 width of the forepart of the insole, the subsequent trimming operations, as shown at 12, at the left of Fig. 5, completing the reinforced sewing rib for the gemmed insole.

85 My present process greatly simplifies the steps and practices necessary, as well as the handling operations, saving the friction coating or priming on the canvas layer, as well as saving the handling of same, presenting a prepared insole capable of adhering directly to the canvas in its 100 natural state, either with or without the reinforcing coating on the edges, and giving a much more desirable resulting article of manufacture.

With my improved gemmed insole I eliminate 105 entirely the heretofore highly objectionable difficulties of the priming or rubber friction coating or adhesive on the canvas flowing through the sewing needle through the inseam stitching operation, which gummed up the needle and thread and rendered same highly objectionable. 110

In my completed gemmed insole the canvas or textile being applied to the insole without an adhesive coating thereon permits a cleaner and faster inseam stitching operation, as well as 5 affording a snugger fit at the base of the sewing rib, producing a much better and uniformly stronger reinforcing welt insole.

I claim:

The improved process of making gemmed in-10 soles, comprising the steps of channeling an insole blank to form a sewing rib, then coating the flesh side of said blank with an adhesive ca-

pable of adhering to unprimed textile material, applying to the channeled and coated blank a textile reinforcing layer having an unprimed portion and an edge portion treated with an adhesive to prevent the edge from unraveling, fitting 80 the unprimed portion to the base of the sewing rib and a part of the adhesive coated edge being adjacent the top of the sewing rib, trimming off the surplus reinforcing material, and completing by the usual processes.
